(57) **CLAIM**

The ornamental design for a mop with dual head, as shown and described.

DESCRIPTION

FIG. 1 is a front elevational view of the mop with dual head of the present invention, the rear view being a mirror image thereof;

FIG. 2 is a left side elevational view of the mop with dual head of FIG. 1;

FIG. 3 is a right side elevational view of the mop with dual head of FIG. 1;

FIG. 4 is a top plan view of the mop with dual head of FIG. 1; and,

FIG. 5 is a bottom plan view of the mop with dual head of FIG. 1.

The handle is shown broken away to indicate indeterminate length.
